BURIAL BOX

Andrew F. Howe, University City, Mo.

Application December 29, 1938, Serial No. 248,147

6 Claims. (Cl. 72—7)

This invention relates to burial boxes.

Objects of the invention are to provide an improved burial box of the type used to enclose the usual caskets, which box is composed of reinforced concrete slabs assembled in a relationship to form a complete box which is substantially leak-proof and which, because of its mineral composition, is considered to be everlasting and will protect and enclose the casket therein indefinitely; to form the slabs with novel interlocking joints permitting easy and rapid assembly of the box within the grave preparatory for the application of the lid or cover; to provide a box of this character having a lid inclining in opposite directions from the center so that water is caused to move or flow from the lid to the sides of the box; and to provide such a burial box having reinforcing devices embedded within the slabs thereof to strengthen them and diminish likelihood of breakage or damage.

Other objects will appear from the following description, reference being made to the annexed drawings, in which—

Fig. 1 is a perspective view of my improved burial box.

Fig. 2 is a side elevation.

Fig. 3 is a top plan view of the complete box.

Fig. 4 is a plan view of the box before the lid is applied thereto.

Fig. 5 is an end elevation.

Fig. 6 is a cross-sectional view on the line 6—6 of Fig. 3.

Fig. 7 is a sectional view showing a different form of joint between the outer edges of the lid and the upper edges of the side walls of the box.

Fig. 8 is an enlarged view showing a detail of the joint formation on the ends of the end walls for engagement with the adjacent ends of the side walls of the box.

Fig. 9 is a view showing further details of the interlocking joints securing the side walls to the end walls of the box.

Fig. 10 is an end view of a portion of one of the side walls showing the construction thereof for interlocking engagement with the end wall of the box.

The entire box is composed of concrete slabs shaped and formed in order to provide portions for cooperative engagement with the adjacent portions of other slabs to hold all of the slabs in assembled relationship so that, when the box is formed and placed in use, the various slabs cannot readily become detached or moved apart. The individual slabs of concrete embed reinforcing means, such as interlocking rods or woven

screen, which diminish likelihood of damage or deformation.

The side wall slabs 1 embed the reinforcing elements 2 of crossed rods or wires which may be in the form of screen material or the like. 5 These slabs extend the full length of the box and have spaced supporting shoulders 3 near their upper margins which extend inwardly.

The vertical end slabs 4 are also composed of concrete and embed similar reinforcing materials. The upper edges of the end slabs incline upwardly and rearwardly from the side edges thereof to points 5. The two slabs 6 forming the lid or cover of the box are laid upon the upper edges of the end walls and incline downwardly in 15 opposite directions to seat upon the upper edges of the side walls 1 and embed reinforcements 7 similar to the reinforcements 2. Downwardly extended flanges 8 formed integral with the slabs 7 engage against the inside of the upper margins 20 of the side slabs 2 and hold the lid slabs 6 in a relationship in which the adjacent edges thereof are in close contact to form a substantially hermetic or leakproof joint and in which the lower edges thereof extend outwardly over the 25 upper edges of the side slabs 1 (Figs. 5 and 6). Downwardly extended flanges 9 integral with the end margins of the cover slabs 6 engage against the inner sides of the end slabs 4 and hold said slabs from endwise displacement. Cross 30 members 10 are seated upon the shoulders 3 and have upper edges inclining in accordance with the inclination of the slabs 6 and engage against the undersides of transverse ribs or flanges 11 formed in connection with the inner sides of the 35 slabs 6 so as to support the intermediate portions of said slabs.

The bottom of the box comprises two slabs 12 and 13 composed of concrete or the like and embedding metallic reinforcing elements 14 of 40 crossed rods or wires or screen material, such as the reinforcements 2 and 7. Each of the bottom slabs is formed with an upwardly extended flange 15 near its outer side margin and with a transverse flange 16 near each end margin. These 45 flanges are spaced inwardly from the outer edges and ends of the slabs a distance approximately equal to the thickness of the side wall slabs 1 and the end wall slabs 4 respectively so that, when said side and end slabs are assembled upon the 50 bottom slabs, they seat upon the bottom slabs at the outer sides of the flanges 15 and 16 respectively and are held from inward movement thereby. At spaced intervals, the bottom slabs have integral upwardly extended supporting flanges 17 55

the inner ends of which are connected by flanges 18 extending along the inner edges of the bottom slabs between the flanges 17. The ends of the bottom slabs are formed with inwardly extended flanges 19, and all of the flanges 17, 18 and 19 cooperate to strengthen the bottom slabs and also function to support the casket above and out of direct contact with the bottom slabs of the box.

The side wall slabs 1 and the end wall slabs 4 are interlocked in such a way as to prevent any of said walls from becoming disarranged and to prevent collapse of the box. The ends of the side wall slabs 1 are formed with tenon extensions 20 which seat against the ends of the end slabs 4. The lower edges 21 of the tenon extensions 20 incline downwardly and outwardly from the ends of the side walls 1 and incline downwardly and inwardly from the outer surfaces of the side walls 1 (Figs. 9 and 10). The ends of the end slabs 4 are formed with tenon extensions 22 which seat against the ends of the side walls 1. The upper edges of the tenon extensions 22 are formed with walls 23 complementary to the walls 21. The walls 23 incline upwardly and outwardly from the ends of the slabs 4 and incline downwardly and outwardly from the inner surfaces of said slabs 4. When the side and end wall slabs are assembled upon the bottom slabs of the box, the tenon extensions 20 seat upon the tenon extensions 22 and the tenon walls 21 and 23 interlock so that it is impossible for the walls to become disarranged or collapse. The only way in which the box can be disassembled is to raise the side walls 1 vertically to disengage the tenon devices 20 from interlocking devices of the tenon devices 22. By this interlocking tenon arrangement, the side and end walls of the box are held rigidly upon the bottom slabs in position to receive the transverse supporting members 10 and the cover slabs 6 to complete the box.

In the box already described, the joints of the respective parts are made to fit together accurately. It will be apparent that any sealing substance or material may be applied to the joints to make the box almost completely impervious. In the modification shown in Fig. 7, the upper edges of the side slabs 1' are rounded so as to facilitate the placing of the top slabs 6' thereon. In this construction, a sealing substance 24 may be applied in the joint formed by the slabs 1' and the slabs 6'.

The parts of my improved burial box may be manufactured in quantities and kept in storage for use as required. My invention dispenses with the use of bolts and rivets and other fastening devices commonly used in assembling burial boxes of all types with which I am familiar and which are now used. These slabs may be manufactured and transported at low cost because of the fact that the usual protruding fastening devices are omitted, and also because the slabs may be laid flatwise one upon the other. When properly reinforced, the slabs may be made comparatively thin and are, therefore, not so heavy as to require the use of derricks and other hoisting mechanisms in transporting or in placing the box in position for use.

The invention may be varied within the scope of equivalent limits without departure from the nature and principle thereof.

I claim:

1. In a burial box having all of its walls composed of concrete slabs, flanges extending upwardly from the bottom of the box and spaced

inwardly from the edges thereof, the side and end slabs of the box being seated upon the bottom at the outer sides of said flanges, interlocking tenon devices integral with the ends of the side and end slabs holding them in vertical positions upon the bottom as aforesaid, a pair of longitudinal cover slabs extending the full length of the box seated upon the upper edges of the side and end slabs, cross members cooperating with the side and end walls to support said cover slabs, and flanges integral with the undersides of said cover slabs engaging against the inner surfaces of the side and end slabs of the box and holding the adjacent longitudinal edges of said slabs in abutting contact.

2. In a burial box having all of its walls composed of concrete slabs, flanges extending upwardly from the bottom of the box and spaced inwardly from the sides thereof, the side and end slabs of the box being seated upon the bottom at the outer sides of said flanges, interlocking tenon devices integral with the ends of the side and end slabs holding them in vertical positions upon the bottom as aforesaid, a pair of longitudinal cover slabs extending the full length of the box seated upon the upper edges of the side and end slabs, cross members cooperating with the side and end walls to support said cover slabs, flanges integral with the undersides of said cover slabs engaging against the inner surfaces of the side and end slabs of the box and holding the adjacent longitudinal edges of said slabs in abutting contact, vertical flanges extending upwardly from the bottom of the box for strengthening the same and supporting a casket, and spaced transverse supporting members carried by the side slabs of the box and supporting intermediate portions of the cover slabs.

3. In a burial box comprising bottom, side, end, and a pair of duplicate longitudinal cover walls all of which are composed of concrete slabs; interlocking tenon devices integral with said side and end walls preventing lateral displacement of either of said walls when said walls are assembled upon the bottom wall, means integral with the bottom wall engaging said side and end walls cooperating with said tenon devices to hold all of said walls in rigid relationship, elements supported by said side walls supporting intermediate portions of said cover walls, and means for holding the cover walls of said box from lateral displacement upon said side and end walls and engaging said side and end walls to prevent lateral displacement thereof.

4. In a burial box comprising bottom, side, end, and a pair of longitudinal cover walls all of which are composed of concrete slabs; parts on said side and end walls respectively abutting against the outer ends of the adjacent end and side walls respectively, interlocking tenon devices integral with the side and end walls preventing lateral displacement of said side and end walls from each other and holding said walls in vertical position upon the bottom walls of the box, elements cooperating with said end walls and said side walls to support said cover walls in edgewise abutting contact and inclined downwardly in opposite directions towards the side of the box, and means in connection with said cover walls engaging the inner surfaces of the side and end walls and holding the cover walls from lateral and longitudinal displacement and the side and end walls from inward movement.

5. In a burial box comprising bottom, side, end, and a pair of longitudinal cover walls all

of which are composed of concrete slabs; parts on said side and end walls respectively abutting against the outer ends of the adjacent end and side walls respectively, interlocking tenon devices 5 integral with the side and end walls preventing lateral displacement of said side and end walls from each other and holding said walls in vertical position upon the bottom walls of the box, means in connection with said cover walls engaging 10 the inner surfaces of the side and end walls and holding the cover walls from lateral and longitudinal displacement and the side and end walls from inward movement, and detachable supporting members mounted on said side walls and engaging and supporting said cover walls between 15 the ends thereof.

6. In a box comprising bottom, side, and end walls, all of which are composed of concrete

slabs; interlocking tenon devices integral with said side and end walls preventing lateral displacement of either of said walls when they are assembled upon the bottom wall, means integral with said bottom wall engaging said side and end 5 walls and cooperating with said tenon devices to hold all of said walls in rigid relationship, a pair of longitudinal cover slabs extending the full length of the box, upwardly extended portions integral with said end walls supporting said slabs 10 in edgewise abutting contact and inclining downwardly and laterally toward the sides of the box, elements supported by said side walls engaging and supporting intermediate portions of said cover walls, and means for holding said cover 15 walls from lateral and longitudinal displacement.

ANDREW F. HOWE.
